UNITED STATES PATENT OFFICE

ROBERT C. PAULY, OF AVONDALE, OHIO, ASSIGNOR TO THE AMERICAN LAUNDRY MACHINERY COMPANY, OF CINCINNATI, OHIO, A CORPORATION OF OHIO

PRESSING MACHINE

Application filed June 22, 1928. Serial No. 287,392.

This invention relates to pressing machines and particularly to controlling mechanism for presses of the full automatic type although the invention in some respects has application to power mechanism applied to final pressure means utilized in conjunction with the hand closed and after power type of pressing machine.

With the application of power to pressing machines of the full automatic type and the hand closed and after power type, it is important, especially where the motor is started and stopped for each power part cycle, that brake means be used and that it be controlled in proper step with respect to the other controls so that the part cycles of the power mechanism be clearly and properly defined.

The present invention therefore relates to mechanism for co-relating the operation of the brake means with the operation of the control means so that the brake is applied and released at the proper time with respect to the power means, and specifically, so that the application of the brake will always be accompanied by the disconnecting of the motor circuit of the power means and vice versa.

The invention will be more fully brought out in the following description, drawings and claims.

In the drawings, Fig. 1 shows a type of pressing machine to which the invention is applied and also shows certain details of the mechanism used in bringing about the invention; Fig. 2 is a view partly in horizontal section and partly in plan showing some of the mechanism; Fig. 3 is a perspective view of the motor and brake control mechanism with parts removed and broken away; Fig. 4 is a detailed view showing one of the operator operated controlling devices; Fig. 5 is a similar view looking at the rear of this device; Fig. 6 is a detailed view of the brake mechanism; Fig. 7 is a view of this same mechanism in side elevation; Fig. 8 is a view in section and broken away showing the controller of the switch mechanism; Fig. 9 is a section upon the line 9—9 of Fig. 8; Fig. 10 is a cross sectional view taken back of the switch fingers and showing the switch throwing mechanism on the end of the crank shaft;

Fig. 11 is a similar view showing the parts in another position; Fig. 12 is a sectional view through the shaft of the switch; and Fig. 13 is a diagrammatic view of the circuit.

In the embodiment shown in the drawings, 55 1 represents a main frame provided with a work board 2, a bed support 3 and a bed or lower buck 4. Projecting upwardly at the back is a head supporting arm 5 carrying a pivot 6 upon which a head lever is pivoted. 60 This head lever comprises a forwardly extending portion 7 carrying the head 8 and a rearwardly extending portion 9 having spaced side portions as indicated in Fig. 1. These spaced side portions 9^a carry studs 10 pivotally supporting the swivel block 11. They also support a saddle or yoke 12 also pivoted on these studs and adapted to swing over the head 13 of a push rod 14 extending downward at the rear and pivotally connected 65 at 15 to a link 16 in turn pivoted at 17 to the rear short arm 18 of a power applying lever 19. This lever is pivoted on the frame at 19'. Pivoted at the point 15 is another link 20 extending toward the front and connected to 70 the outer end of a press closing lever 21 pivoted at 22 to the frame. This lever is provided with a diagonal slot 23 adapted to be engaged by a roller 24 mounted upon the upper end of an arm 25 forming a part of the 75 lever 19. This lever 19 is connected at 26 to a link 27 connected in turn at 28 to a crank 29 on the crank shaft 30. The head lever normally assumes open position or that shown in Fig. 1, by reason of the action of a spring 80 31 connected to the head trunnions 10 and to the pivot 19' of the power lever.

The saddle or yoke 12 is provided with a downwardly and rearwardly extending arm 32 connected by a rod 33 with a two-armed 85 lever 34 pivoted in the frame at 35 and having its lower short arm connected by a pull rod 36 with the rear lever arm 37 of a hand lever 38 at the front of the machine and supported for movement at the front edge of the 90 work board 2.

The crank shaft 30 is driven by a suitable worm wheel 39 operated by a worm 40 on a worm shaft 41 all arranged in a worm housing and connected by a coupling 42 to a suit- 100

able motor 43 mounted upon a suitable platform 44 secured to the frame.

The mechanism thus far described merely sets forth a type of press upon which this invention may be utilized and forms no part of this invention except in so far as it may enter into the organization.

The control and brake mechanism will now be described. Secured to the frame at 10 the end of the shaft 30 is a controller box 45 having mounted therein below the axis of the shaft 30, but in parallel alignment therewith, a switch actuating shaft 46 carrying a pair of insulating blocks 47 and 48, 15 Fig. 12. These insulating blocks carry conducting bridges 49, 50, 51 and 52 respectively, adapted to cooperate with conducting fingers 53, 54, 55 and 56 for establishing the proper circuits, as will later appear. 20 These fingers are supported upon a suitable rod or bar 57 carried by the box 45. The shaft 46 is also provided with a suitable pinion 58, Figs. 10 and 11, adapted to mesh with a rack 59 forming a part of an actuating rod 60 mounted to slide in suitable bearings in the box and extend out at the rear where it is provided with a suitable clevis 61. The rod 60 is also provided with up-standing fingers 62 and 63 separated and 30 extending on both sides of a switch neutralizing mechanism comprising a disk 64 rigidly secured to the end of the crank shaft 30 and of mutilated form providing a tail portion 65 to the rear of a roller 66. The 35 direction of rotation of the shaft 30 is clockwise, as shown in Fig. 10. The disk 64 also has pivoted to it at 67 a lever 68 extending on both sides of the pivot and provided at one end with a roller 69 and at the other 40 end connected to a spring 70 adapted to throw the roller 69 outward. The mechanism just described is for the purpose of engaging the fingers 62 and 63 and moving the switch back to neutral position for the 45 establishment of the part cycles of the machine, as will later appear.

If necessary, the rod 60 may be prevented from being moved accidentally by a spring pressed ball 60' suitably supported on the 50 box 45 and engaging in a suitable recess 60" in the shaft and so located that it registers with the ball when the movable switch element, comprising the members 47 and 48, is in neutral position as shown in Fig. 9.

Secured to the box 45 is a lever bracket 71, Fig. 9, supporting a switch actuating lever 72 pivoted intermediate its ends to the bracket at 73. The lower end of this lever is connected in the clevis 61 while the upper 55 end is connected to a pull rod 74 extending over the box and pivotally connected at a point 75 to a lever 76 which is pivoted at 77 to the frame of the worm housing. This lever projects upward, as clearly shown in Fig. 8, and is connected at its upper end as

at 78 to a pull rod 79 extending upwardly and forwardly where it engages a downwardly extending arm 80 of a hand lever 81 pivoted at 82 to a bracket 83 secured to the underside of the front edge of the work board 2. The bracket 83 is provided with a keeper 84 adapted to be engaged by the hook 85 of a latch lever 86 pivoted at 87 to the handle 81 and forced into a position to engage the keeper by a suitable spring 88.

It will be seen from the foregoing and with particular reference to Fig. 4, that the operator may grasp the handle 81, actuate the latch 86 and release the handle so that it may be depressed. The depression of this handle causes the lever 72 to be moved in a counter-clockwise direction moving switch rod 60 to the right, as shown in Figs. 9, 10 and 11, causing certain switch operations which will be described.

The coupling member 42 is provided with a brake drum 42' and it is adapted to be engaged by a brake band 89 adjustably dead ended at 90 in a frame part 91 secured to the platform 44 and having at its upper end spaced bearings 92 and 93. This frame part 91 is braced by a suitable bracket 94. The bearings 92 and 93 support the brake actuating rod 95 which is provided between the bearings, 92 and 93, with a brake release actuator in the form of a double cone comprising the high cone parts 96 and the low cone part 97. Beyond the bearing 92, the rod 95 receives a thrust spring 98 thrusting against the bearing and against a collar 99 secured to the rod. The tendency of this spring is to thrust this rod to the left, as shown in Fig. 6, thereby setting the brake and returning the controller to neutral or off position. The rod at its opposite end is provided with a clevis 100 pivotally connected to the lever 76, as shown in Fig. 3. The frame part 91 also supports a push rod 101 pivotally connected to the loose end of the brake band. The push rod 101 carries at its upper end a thrust washer 102 engaging a spring 103 between it and a stationary part of the frame part 91. This spring normally tends to set the brake and when the push rod is opposite to the low point 97 of the double cone, it produces braking action upon the brake drum and contrariwise, when the rod 95 is shifted to one side or the other, the push rod is moved downward by parts of the double cone and the brake is released.

The electric circuit for the motor means is illustrated in Fig. 13 and in such view the circuit for closing the press from full open to full final pressure position is from L¹ through the left hand blade of the switch 104 through the line 105 to the contact 56, from thence through the bridge contact 49, which has been moved to the point of engaging the contact 56, to the contact 55, thence through

85

100

105

110

115

120

125

130

the line 106 to the motor 43, thence through the line 107 to the contact 53, thence across the bridge contact 51 to the contact 54 and thence through the line 108 to the right hand blade of the switch 104 to L^2 . For the release operation, the same circuiting takes place except that in place of the bridge contacts 49 and 51 being in engagement with the contacts 56, 55, 54, 53, the bridge contacts 50 and 52 are used, they being thrown into operative position by proper movement of the rod 60.

When the press is in idle open position, the parts of the switch mechanism are as shown in Fig. 9 with the bridge contacts 49 and 51 to the right and the bridge contacts 50 and 52 to the left and both sets of such bridge contacts out of contact with the fingers 56, 55, 54 and 53. When the parts are in this position the rod 60 cannot be moved to the right by the control lever 81 but can only be moved to the left, because the roller 66 is in a position to obstruct movement to the right. Therefore, when the operator wishes to close the press he elevates the control member 81 moving the lever 72 clockwise and shifting the rod 60 to the left. This brings the bridge contacts 49 and 51 into engagement with the fingers 56, 55, 54 and 53 and brings about the operation of the motor and the closing of the press to full pressure position. During the closing movement however, the member 64, Fig. 10, has moved from the position indicated in Figs. 9 and 11 to the position shown in Fig. 10 when the roller 66 will engage the finger 63 and move the switch blocks 47 and 48 from the dotted line position to the left in Fig. 9 to the full line position in that figure when the motor circuit will be broken and the press will stand closed. It is also obvious that the roller 69 will be yieldingly pressed against the finger 62 and this may be overcome by the operator moving the handle 81 downward and thereby rocking the lever 72 counter-clockwise and shifting the rod 60 to the right to the dotted line position shown in Fig. 9 when the motor circuit will then be closed for the opening operation. The tension of the spring 70 is insufficient in this position of the roller to create any considerable resistance to the movement of the controller to the release position or to return it to neutral position.

As the head approaches the bed and the roller 66 is moving clockwise from the position shown in Fig. 9 to the position shown in Fig. 10, the roller 69 is carried clockwise so that its spring 70 tends to move it into engagement with the finger 62 which would tend to move both the fingers 62 and 63 as well as the switch mechanism to the left, as shown in Fig. 9, or to the one to which they have been originally thrown for the pressing operation. The springs 70 and 98, however,

are so calibrated that the tendency of this roller 69 at this time, which just precedes final pressure and is after safe closing, is sufficient to hold the fingers 62 and 63 to the left and therefore the press can proceed through to final pressure. Before this roller 69 becomes effective for such an operation, however, the strength of the spring 98 is sufficient to return the entire control mechanism and bring the switch into neutral position, or that shown in Fig. 9. As the press finally reaches full pressure position, the roller 66, by engagement with the finger 63, moves the switch mechanism into neutral position, or that shown in Fig. 9, against the tension of the spring 70 controlling the roller 69. When the press is to be opened, the operator presses down upon the control, shifting the lever 72 counter-clockwise and sliding the rod 60 with the fingers 62 and 63 to the right against the tension of the spring 70, causing the proper switch arrangement to produce another operation of the motor and an opening of the press. The roller 66 finally engages the finger 62, throws the switch to open the motor circuit, stops the press and ends up in the position shown in Fig. 9.

It is quite obvious from an inspection of Figs. 9, 10 and 11 that if no other means other than the roller 66 were provided for governing the operation of the controller switch, the operator, after he had started the closing part cycle, might depress the controlling lever 81 into its release operating zone for some unaccountable reason and therefore throw the switch control mechanism out of its proper step. To overcome this, the disk 64 on the crank shaft is provided with a tail portion 65 already referred to. This portion has a peripheral circumferentially extending bridging part forming, so to speak, a continuation of the outer part of the roller 66 and trailing behind it so that as this roller 66 leaves the finger 62, for example, this tail portion follows it and forms a barrier capable of preventing any movement of the switch mechanism other than back to neutral. In other words, it prevents the complete shifting of the switch mechanism from an on position for closing through neutral and to an on position in the opening zone.

It will be seen from the foregoing, that the mechanism described provides means for completely controlling the press, some of the important features being the application of the braking mechanism with other movement of the controlling mechanism, the application of the brake and the interruption of the motor circuit following in rapid succession with the release of the brake prior to the completion of the motor circuit in every instance thereby doing away with subjecting the motor to the brake load. Another important feature is the provision of means for preventing the automatic maintenance of the

motor circuit until the head reaches a safe position and requiring the attention of the operator until the head is safely closed upon the work with additional means for thereafter automatically maintaining the circuit and permitting the controller to be released by the operator but continuing the operation of the mechanism until final pressure is fully applied.

10 What I claim is:

1. In a garment press, a bed, a cooperating movable head, motor means, operative connections from the motor means to the head for closing and opening the press and for applying final pressure, an electric controller for the motor means having a "closing" position for closing the press and applying final pressure, a "neutral" position and an "opening" position for opening the press, means normally tending to move said controller to neutral position to stop the motor means and thus prevent further closing of the press and the production of final pressure, and means for overcoming said last named means as the head approaches a safe closed position with respect to the bed, whereby the motor means may continue and produce final pressure.

2. In a garment press as set forth in claim 1, characterized in that the controller is provided with an operator operated manipulating device and the motor means is provided with an operative connection between it and the controller for holding the controller in the closing position after the head is safely closed with respect to the bed.

3. In a garment press, a bed, a cooperating movable head, motor means, operative connections from the motor means to the head for closing and opening the press, a controller for the motor means, a brake for stopping the spinning of the motor means, and an operative connection between the controller and the brake and including a brake actuator set for actuation to release the brake prior to the movement of the controller to start said motor means.

4. In a garment press as set forth in claim 3, characterized in that the controller has movement in one direction to close the press and in another direction to open the press and in that the brake is provided with a double acting actuator set to release the brake prior to the actuation of the controller to start the motor means for either closing the press or opening the press.

5. In a garment press, a bed, a cooperating movable head, motor means, operative connections from the motor means to the head for closing and opening the press, a controller for the motor means having a stationary controller element and a movable controller element, said movable controller element having a neutral position and two press operating positions, namely, a press closing operating position, and a press open-

ing operating position, operator operated means for moving said movable controller element to either the press closing position or the press opening position, neutralizing means operated by the motor means for returning the movable controller element to neutral position, and means for preventing movement of the movable controller element to a second press operating position from a first press operating position to which it has been moved by the operator until after the intended press operation has been substantially completed.

6. In a garment press as set forth in claim 5, characterized in that the neutralizing means includes an operative connection between the motor means and the controller for moving the movable controller element of the controller to neutral position at the termination of the press closing operation and the press opening operation.

7. In a garment press as set forth in claim 5, characterized in that an additional neutralizing means is provided tending normally to move the movable controller element of the controller to neutral position during the press closing operation.

8. In a garment press as set forth in claim 5, characterized in that additional neutralizing means is provided tending normally to move the movable element of the controller to neutral position during the press closing operation and in that means is provided for overcoming this tendency of said additional neutralizing means after the head has reached a safe closed position with respect to the bed in the closing of the press.

9. In a garment press as set forth in claim 5, characterized in that additional neutralizing means is provided tending normally to move the movable element of the controller to neutral position during the press closing operation and in that means is provided operatively connected to the motor means and to the movable element of the controller and having a controlling element operated by the power means and rendered capable thereby of overcoming the tendency of said additional neutralizing means after the head has reached a safe closed position with respect to the bed in the closing of the press.

10. In a garment press, a bed, a cooperating movable head, motor means, operating connections from the motor means to the head for closing and opening the press, a controller for the motor means having a movable controller element, brake means for the motor means, a movable actuator for said brake means, an operator operated device for actuating said brake means and said controller, and connections between said controller and said operator operated device, the parts being so constructed and arranged as to cause the controller to release the brake means prior to the actuation of the con-

70

troller to start the motor means and to cause the controller to apply the brake means after said motor means has been stopped.

11. In a garment press as set forth in
5 claim 10, characterized in that the controller has two positions, one for closing the press and the other for opening the press and in that double acting parts are provided to bring about the release of the brake means
10 upon the starting of the motor means and the application of the brake means upon the stopping of the motor means.

In testimony whereof I hereby affix my
signature.
